MACHINE GUN SAFETY DEVICE

George W. Gunner, Eggertsville, and Robert J. Bartholomew, Rochester, N. Y., assignors to Curtiss-Wright Corporation, a corporation of Delaware

Application October 26, 1943, Serial No. 507,754

4 Claims. (Cl. 89—27)

1

This invention relates to a device for preventing uncontrolled firing of machine guns. More particularly, it relates to such a device wherein the breech bolt of the machine gun is held in a rearward position when it is desired not to fire the gun.

When a conventional machine gun is loaded and is ready for use under actual or simulated battle conditions, it is desirable to have it ready for instant operation at all times. In guns of the Browning type, this is normally accomplished by having a cartridge in the firing chamber whenever the gun is not actually being fired. The gun is fired by simply raising the rear end of a fulcrumed trigger bar (by means of a hand-operated or solenoid-operated trigger), and the gun continues to fire as long as the trigger bar is kept in position. Cartridges are actually fired only when the chamber is closed, i. e., the breech bolt is in the forwardmost position.

The difficulty with this method of operation is that, when the gun becomes overheated during firing, it is possible that the cartridge in the hot chamber will be exploded or discharged even when the trigger bar is in the inoperative (rear end lowered) position. This is known as uncontrolled firing due to "cooking" of the cartridge. Serious accidents may result from this.

It is therefore an object of this invention to provide a simple mechanical device, which may be used in combination with the conventional trigger mechanism in a machine gun, to prevent uncontrolled firing of a machine gun. It is another object to provide such a device which will hold the breech bolt of a machine gun in the rearmost position when the gun is not actually being fired (except before firing the first cartridge). Still another object is to provide means for permitting the chamber and barrel of a machine gun to be open between bursts of firing, thus furnishing an additional cooling effect. Other objects will appear hereinafter.

These objects are accomplished by means of a safety device known as the breech bolt hold-back device, and which may be more readily understood by reference to the accompanying drawings.

In the drawings, Figure 1 is a side view of a conventional machine gun of the Browning type, to which the novel hold-back device has been applied, the breech bolt being in the held-back position; Figure 2 is a side view, partly in elevation and partly in cross section, of a portion of Figure 1 on an enlarged scale; Figure 3 is a view taken along the line 3—3 of Figure 2; Figure 4 is a view taken along the line 4—4 of Figure 2; Figure 5

2

is a view taken along the line 5—5 of Figure 2; Figure 6 is a view corresponding to Figure 2, but with the breech bolt released and on its way forward; Figure 7 is a view corresponding to Figure 6 with the trigger bar in the active or firing position; Figure 8 is a view taken along the line 8—8 of Figure 7; Figure 9 is a perspective view showing the trigger mechanism according to the present invention; and Figure 10 is a fragmentary sectional view taken in a plane normal to the planes of Figures 2 and 3 showing a safety lock for the gun.

Referring now to the drawings, a conventional machine gun of the Browning type is indicated at 15 (Figure 1). In the form shown in the drawings, the gun is operated by a solenoid 16, whose plunger 21 moves forward in response to the impulse of an electric current. This plunger is normally held in the rearmost position (see Figures 20 2, 3, and 6) by means of a spring (not shown) when the current is turned off. Thus this form is particularly applicable to use where remote control is desired, such as in fighter aircraft. However, the invention is equally applicable to 25 a gun operated by a direct hand-operated pusher.

The solenoid 16 is held in place on the buffer 17 by means of extensions 18 and bolts 19. Part of the breech bolt mechanism of the gun is indicated generally at 20, and is shown in Figures 2 30 to 5 inclusive in its rearmost position, abutting against the buffer plate 26. Also in Figures 2, 3 and 6 inclusive, the trigger bar 22 is shown in its inactive or non-firing position.

The frame 34 of the breech bolt hold-back 35 mechanism is fastened to the back plate 23 of the gun by means of bolts or screws 30. On this frame is fixed a pin 33, upon which two cam-surfaced levers 31 and 32 are pivotally mounted or journaled, the cam surfaces of these levers to 40 which reference is made being the surfaces engaged by the plunger 21. The rear ends of these two levers are normally kept in the upward position (i. e., the levers are urged in the clockwise direction) by means of two springs 35 and 36 respectively, when the solenoid plunger 21 is in the inactive or rearmost position. These springs are mounted between a horizontally extending arm 37 of the frame 34 and the bottom surfaces of the levers 31 and 32.

50 The forward ends of the levers 31 and 32 pass through an opening 24 in the back plate 23 of the gun. The trigger of a gun not provided with the novel hold-back mechanism of this invention customarily passes through this opening, so that no modification of the back plate (other

than mounting the bolts 30) is necessary in the practice of this invention. The lever 31 in the position shown in Figures 2 and 3 is held in place by the coil spring 35. In this position it rests on the bottom edge of the opening 24, and is prevented from further movement in the clockwise direction by such bottom edge. When the breech bolt 20 is in the rearmost position (Figures 2 and 3), lever 31 catches a notched surface 25 of the breech bolt, and holds it in the rearmost position. Lever 32, in the position shown in Figures 2 and 3, is also prevented from further movement in the clockwise direction by means of a stop 38. At the same time the trigger bar 22 is in the down or inactive position. Lever 32 is held in the position shown in Figure 2 by means of a coil spring 36.

Lever 32 is provided with a horizontally extending projection 39 adjacent its bottom edge. When the lever 32 is rotated in a counter-clockwise direction by means of the solenoid plunger 21 against the action of spring 36, the top surface of this projection 39 is engaged by a leaf spring 40 (see Figure 8 for the activated position) and held in this position against the action of the spring 36. In this position an upwardly extending projection 41 at the forward end of the lever 32 pushes upward against and actuates the trigger bar 22.

The operation of the device is as follows: When the gun is to be prepared for use in actual combat, the loading crew sets the device in the position shown in Figures 2 to 4, inclusive, of the drawings. In this position the breech bolt 20 is held back by the lever 31, and the trigger bar 22 is in the down or inactive position. To accomplish this, the loading crew releases lever 32 by pressing the leaf spring 40 outwardly (towards the right in Figure 8 to arrive at the position shown in Figure 4) with the thumb or finger. The gun is loaded in the customary fashion, the breech bolt being released by pressing down on the cam surface of the lever 31 with the thumb or finger. In doing this it is important that the lever 32 is not actuated, since this will cause the gun to fire. The gun may be prevented from firing during these operations by providing an auxiliary safety mechanism or stop (not shown) for preventing upward movement of the trigger bar 22. For example, as shown in Figure 10, the gun may be provided with a turn lock 42 which when turned to the position illustrated holds the trigger bar 22 in its lower or inactive position, and which, when turned 90 degrees about pivot axis 43 from the position illustrated, is disposed entirely to one side of the bar 22 so that the latter may be raised to firing position. The position of the mechanism when the lever 31 is released, and the breech bolt is on the way forward, is indicated in Figure 6. When the breech bolt is completely forward, the gun is loaded and ready for firing, with a cartridge in the chamber.

When it is desired to fire the gun for the first time after loading, the solenoid 15 is actuated, causing the plunger 21 to move forward, thus pushing downwardly on the cam surface of levers 31 and 32. This position is shown in Figures 7 and 8 of the drawings. Since the breech bolt 20 is already in the forward position, this movement of the lever 31 has no effect on the breech bolt. Movement of lever 32, however, including upward movement of projection 41, causes the trigger bar 22 to move upward, thus firing the gun. At the same time, the leaf spring 40 will engage the projection 39, so that henceforth the

trigger bar 22 will remain in the active position, uninfluenced by the solenoid plunger 21. The gun will continue to fire as long as the solenoid plunger holds the lever 31 in the position shown in Figures 7 and 8.

When it is desired to cease firing, the electric current is shut off, releasing the solenoid plunger and returning it to the rearmost position. Due to the action of the leaf spring 40, cartridges will continue to fire as long as the breech bolt is in the forward position and there is a cartridge in the chamber. When the last shot is fired after releasing the solenoid, however, the lever 31 falls into the notch 25 of the breech bolt 20 on its recoil stroke, and holds it in this position until it is desired to fire the gun again. Thus it is seen that, between bursts of firing, the chamber is empty and the breech bolt is held back, and uncontrolled firing of the gun is prevented. Since the chamber is open, cooling of the barrel and chamber is thus facilitated.

When it is desired to fire the gun again, the current is turned on, causing the solenoid plunger 21 to move forward as before. This has no effect on the lever 32, since it is already held in the active position by means of the leaf spring 40. Pressing down on the cam surface of lever 31, however, releases the breech bolt, causing a cartridge to be injected into the chamber and the gun to be fired immediately thereafter. Firing will continue as long as the lever 31 is held in this position (see Figures 7 and 8).

From the above description and drawings, it will be seen that there is provided a simple and novel mechanism, which can be incorporated in existing machine guns without modification, and which will accomplish all the objects of the present invention. In addition, particularly when used in aircraft installations, an important advantage is due to the fact that the chamber is kept closed before firing the first cartridge. Thus, the gun is protected from dust and other debris during the take-off of airplanes or other periods of rough usage.

It is obvious that many changes may be made in the above-described embodiment of the invention without departing from the spirit thereof. For example, the breech bolt need not be held in its rearmost position, but only sufficiently far to the rear that a cartridge is not held in the chamber. It is understood that the invention is only to be limited as defined in the appended claims.

We claim:

1. In a machine gun of the type having a breech bolt movable between open and closed positions, a firing mechanism element movable between an active and an inactive position, and adapted to fire only when the breech bolt is in closed position and the firing mechanism element is in active position, the combination comprising a first pivoted lever and spring means for urging it into latching engagement with the breech bolt when the latter is in open position, a second pivoted lever for moving the firing mechanism element to active position and spring means for resiliently holding said second lever against such movement, a common actuating plunger for said levers for simultaneously swinging them about their pivots against the resistance of their spring means to effect movement of the firing element to active position and to allow the breech bolt to move free of the latching engagement with the first lever, and resilient detent means engageable with the second lever when the latter has been so moved

for automatically holding the second lever and the firing mechanism element in active position.

2. In a machine gun of the type having a breech bolt movable between open and closed positions, a firing mechanism element movable between an active and an inactive position, and adapted to fire only when the breech bolt is in closed position and the firing mechanism element is in active position: the combination comprising a first member having resilient means for urging it into latching engagement with the breech bolt when the latter is in open position, a second member for moving the firing mechanism element from inactive position to active position, a common actuator for said members for simultaneously moving them to effect movement of the firing element to active position and to allow the breech bolt to move free of the latching engagement with the first member, and detent means operable by and upon such movement of the second member for holding the firing mechanism element in active position.

3. In a machine gun of the type having a breech bolt movable between open and closed positions, a firing mechanism element movable between an active and an inactive position, and adapted to fire only when the breech bolt is in closed position and the firing mechanism element is in active position: the combination comprising a first member having resilient means for urging it into latching engagement with the breech bolt when the latter is in open position, a second member for moving the firing mechanism element to active position, a common actuator for said members for simultaneously moving them to effect movement of the firing element to active position and to allow the breech bolt to move free of the

latching engagement with the first member, and detent means operable by and upon such movement of the second member for holding the second member and the firing mechanism element in active position.

4. In a machine gun of the type having a breech bolt movable between open and closed positions, a firing mechanism element movable between an active and inactive position, and adapted to fire only when the breech bolt is in closed position and the firing mechanism element is in active position: the combination comprising means for latching engagement with the breech bolt when the latter is in open position, means for moving the firing mechanism element to active position, a common actuator for the aforementioned means for simultaneously operating them to effect movement of the firing element to active position and to allow the breech bolt to move free of the latching means, and detent means automatically operable upon the first movement of the firing mechanism element to active position for holding the latter in said active position.
